UNITED STATES PATENT OFFICE.

ROBERT L. DUKE, OF COLUMBUS, GEORGIA.

SPINNING OR WINDING MACHINE.

Application filed July 29, 1921. Serial No. 488,325.

To all whom it may concern:

Be it known that I, ROBERT L. DUKE, a citizen of the United States, and a resident of Columbus, in the county of Muscogee and State of Georgia, have invented certain new and useful Improvements in Spinning or Winding Machines, and do hereby declare the following to be a full, clear, and exact description of the invention, such as will enable others skilled in the art to which it appertains to make and use the same.

This invention relates to an improvement in spinning or winding machines in which means are employed for traversing the thread guides to build up the bobbin,—my improvements having particular reference to "bunch" building attachments for spinning machines such as employ ring rails and operating means therefor to effect traverse of the thread. One object of my invention is to provide a "buncher" attachment for bobbins used in automatic looms, which shall be simple in construction; which shall be controlled by the operation of the "builder" mechanism, and which will result in causing a reduction of waste by allowing a maximum amount of yarn to be removed from the bobbin, and prevent thin places in the woven cloth by insuring uniformity in the size of "bunches" which actuate the feelers so that a minimum amount of waste will be left to be cut off the bobbins, thus saving both in material and labor.

With this and other objects in view, the invention consists in certain novel features of construction and combinations of parts as hereinafter set forth and pointed out in the claims.

In the accompanying drawings, Figure 1 is a view illustrating an embodiment of my invention, and Figures 2 to 7 are views illustrating details.

In the drawings, I have illustrated the frame 1 of a spinning machine, on which spindles 2 are suitably mounted to receive bobbins 3. A ring rail such as usually employed in spinning machines of the type to which I have illustrated the application of my improvement, is shown at 4 and with this rail, a lifting rod 5 is connected. The lower end of the lifting rod is provided with a head 6 which is supported on a roll or stud 7 carried by an arm 8 of a bell-crank lever 9. A foot piece 10 is secured to the free end of the arm 8 of the bell-crank lever and an upwardly projecting arm 11 of this

lever is provided with a segment 12. To this segment, one end of a chain 13 is suitably connected and the operation of this chain to move the bell-crank lever and operate the lifting rod 5 to raise the ring rail, is controlled by a builder mechanism illustrated as 14. The mechanism above described is of usual construction and need not be further described in detail herein, except in so far as parts of my improvements are co-operative therewith.

A bracket 15 is secured to and depends from one of the rails of the frame 1 and is provided with a vertical slot 16 in which a stud 17 is adjustably secured. A lock lever 18 is pivotally mounted on the stud 17 and is provided with a weight 19. The depending portion of the lever 18 is made with an elongated slot 20 for the passage of bolts 21 whereby a lock arm 22 is adjustably secured to said lever 18, and in effect constitutes an extension thereof. The arm or lock lever extension 22 is provided near its lower end with a slot or recess 23 which (under certain conditions) receives the free end of the foot piece 10 to lock the traverse mechanism at or near the lower end of the throw thereof and permit the formation of a "bunch" on the lower portion of each bobbin as indicated at 24. The lock lever arm is provided just above the slot or recess 23 with a lug 25 which will prevent locking engagement of the foot piece 10 with the lock lever arm during the normal operation of the mechanism in winding the service thread or yarn on the bobbins. Below the slot or recess 23, the lock lever arm 22 is provided with a lug or toe 26, beneath which the foot piece 10 may be made to engage so that the latter will be held down during doffing.

The locking devices which control the operation of the mechanism for causing the formation of bunches as previously explained, is itself controlled from the builder mechanism. A cam 27 is secured to rotate with the take-up gear 28 on the builder shaft 29,—said cam being disposed between lugs 30—30 projecting laterally from a longitudinally movable bar 31, the latter being made with an elongated slot 32 for the accommodation of the builder shaft 29. The bar 31 is provided with an extension 33 adjustably secured thereto as indicated at 34 whereby said bar as a whole may be lengthened or shortened and the throw of said bar may be

adjusted by adjusting the cam 27 relatively to the gear 28. At its free end, the bar extension 33 is provided with a lug 35 and the lock lever arm 22 is provided with a screw 5 or stud 36 on which bar extension 33 is supported.

When the lock lever arm 22 is in engagement with the foot piece of the traverse mechanism to lock the latter during the formation of the "bunches", it will be held in such position by the operation of the weight 19.

After the bunches shall have been formed, the cam 27 will operate to move the bar 31 15 and its extension 33 rearwardly so as to cause the lug 35 on the latter to engage the lower portion of the locking device 18-22 and move the latter so as to release the foot piece 10 and thus permit the normal operation of 20 the machine to effect the winding of the service threads or yarn on the bobbins.

Having fully described my invention what I claim as new and desire to secure by Letters-Patent, is:

25 1. In a spinning machine, the combination with traverse mechanism and builder mechanism cooperable therewith, of a locking device for the traverse mechanism during the formation of bunches, a longitudinally movable bar, and cam means operable by the builder mechanism to move said bar and withdraw the locking device from locked relation relatively to the traverse mechanism.

2. In a spinning machine, the combination 35 with traverse mechanism and builder mechanism cooperable therewith, of a locking device to hold the traverse mechanism during the formation of bunches, a cam adjustably connected with a moving part of the builder mechanism, and a longitudinally movable bar operable by said cam and having a part 40 to engage a part of the locking device and move the latter out of locked relation relatively to the traverse mechanism.

45 3. In a spinning machine, the combination with traverse mechanism and builder mech-

anism cooperable therewith, of a locking device to hold the traverse mechanism during the formation of bunches, a longitudinally movable bar comprising two members, one 50 adjustable longitudinally with respect to the other, and means operable by the builder mechanism for moving said bar longitudinally to release the locking device from the traverse mechanism.

4. In a spinning machine, the combination with a ring rail, a bell-crank lever, a lifting rod between an arm of said lever and the ring rail, builder mechanism cooperable with said bell-crank lever, and a foot piece on said 60 bell-crank lever, of a weighted lock lever provided with an adjustable lock arm having a slot or recess to receive said foot piece, and means operable by the builder mechanism to move said lock arm out of engagement with 65 said foot piece.

5. In a spinning machine, the combination with a frame, traverse mechanism and a builder cooperable with said traverse mechanism, of a bracket secured to the frame, a 70 weighted lever having vertically adjustable pivotal connection with said bracket, a lock arm adjustably connected with said lever and having a slot or recess to receive a part on the traverse mechanism, a lug on the lever 75 above said slot, a lug on the lever below said slot, a longitudinally movable bar comprising relatively adjustable members, a part on the lock arm to support said bar, a part on said bar cooperable with the lock arm to disengage the latter from the traverse mechanism, and means operable by the traverse mechanism for moving said bar longitudinally.

In testimony whereof, I have signed this 85 specification in the presence of two subscribing witnesses.

ROBERT L. DUKE.
